UNITED STATES PATENT OFFICE.

PAUL F. WERNER, OF WILLIMANSETT, MASSACHUSETTS, ASSIGNOR TO COBURN TROLLEY TRACK MANUFACTURING COMPANY, OF HOLYOKE, MASSACHUSETTS, A CORPORATION.

SWITCH FOR OVERHEAD TUBULAR TROLLEY-TRACKS.

SPECIFICATION forming part of Letters Patent No. 706,139, dated August 5, 1902.

Application filed July 11, 1901. Serial No. 67,860. (No model.)

To all whom it may concern:

Be it known that I, PAUL F. WERNER, a citizen of the United States, residing at Willimansett, in the county of Hampden and State of 5 Massachusetts, have invented new and useful Improvements in Switches for Overhead Tubular Trolley-Tracks, of which the following is a specification.

This invention relates to switches for overhead trolley-tracks, and has especial reference to the tubular track construction, the object of the invention being to provide a switch for a track of this description which obviates the necessity of using a pivoted 15 track-section swinging from the main line to one or more side tracks; and the invention consists in providing a plate transversely 20 slidable across the main track and having tubular track-sections thereon adapted to bridge the space between two ends of the main track or between one end of the main track and the end of a side track on either side of the main track.

In the drawings forming part of this application, Figure 1 is a perspective view of an overhead tubular trolley-track having my improved switch applied thereto. Fig. 2 is a perspective view of a plate slidable transversely of the main track. Fig. 3 is a supporting-frame in which said plate slides, also shown in perspective.

Referring now to the drawings, 2 indicates two ends of a divided main track, the extremities of which are supported, respectively, in 35 the brackets 3 and 4 on a frame 5. This frame is preferably made of cast-iron and has the brackets 3 and 4 preferably cast integrally therewith, as shown in Fig. 1, and bolted to the ceiling. On said frame, if there be one 40 side track, as 6, there is provided a suitable bracket 7 therefor, cast on the frame 5 on the right or left hand side of the bracket 4, according to whether the side track 6 be a right or a left hand track. The use of the term 45 "side track" applies to any track entering the main line 2. The frame 5 is provided with a rectangular opening therein for the reception of a plate 8, two opposite edges of which are provided with the flanges 9, which 50 rest on the ledges 10 of the frame 5, the top

of said plate 8 being flush with the top of the frame. On the plate 8 there are cast the track-sections, 11 indicating that for completing the broken main line 2, and 12 indicating that for closing the break between one 55 end of the main line and the end of a branch line, as 6. The dimensions of the rectangular opening in the frame 5 are such that the plate 8 in its sliding movements in said frame may move these track-sections 11 and 12 so 60 that one end of either of these sections may register with the end of the track in the bracket 3, and when one is in registration therewith the end of the other section will be blocked by its abutment against the flange 13 65 on the frame 5. This is a flange lying at right angles to the surface of the frame, which is screwed against the ceiling. Where there are two side tracks entering the main track at the same point, then the frame 5 is made 70 wider and has another bracket, as 7, cast on the other side of the bracket 4, and the plate 8 has another track-section, as 12, cast thereon.

Any suitable means may be employed for imparting to the plate 8 a suitable traverse motion which will bring any one of the track-sections thereon into registration with that end of the main line supported in the bracket 3. In the drawings the means shown consist of a pulley 14, supported on an arm 15, secured to the ceiling. A rope 16 is passed a number of times around the pulley 14, the opposite ends of the rope hanging down within convenient reach of the hand. A crank 17 is secured to the pulley, and a connecting-rod 85 18 extends from the end of said crank to the side of the plate 8, with which it is pivotally connected at 19. By pulling on one end or the other of the rope the plate 8 may be moved in its frame.

It has been found that in tracks of this description which are designed to carry heavy loads the ordinary form of switch swinging from the main to the side tracks is incapable of withstanding the load put upon it; but the 95 device herein described is quite as rigid as the main track itself, and the construction permits of attaining an accurate registration between the ends of the track-sections on the switch-plate and the ends of the track, a fur- 100

ther advantage being that unless the switch-plate is in place the passage of a hanger will be blocked.

Having thus described my invention, what I claim, and desire to secure by Letters Patent of the United States, is—

Switch devices for overhead trolleys comprising the main frame 5 having a rectangular opening therein and the pending brackets 3 and 4, a side bracket 7 thereunder, and the ledges 10 in the opposite borders thereof, combined with the plate 8 having borders for

engagement on said ledges, and slidable in said frame 5, and the track-sections 11 and 12 under said plate 8, registrable with said brackets 3 and 4, through sliding movements of the frame 8 in the frame 5, and means for moving said frame 8, substantially as set forth.

PAUL F. WERNER.
